APPARATUS FOR OIL SAND HEATING

Filed Jan. 4, 1946

UNITED STATES PATENT OFFICE

2,444,755

APPARATUS FOR OIL SAND HEATING

Ralph M. Steffen, North Hollywood, Calif.

Application January 4, 1946, Serial No. 639,125

2 Claims. (Cl. 166—17)

1

This invention relates to an apparatus for oil sand heating.

The primary object of this invention is to provide a novel method and apparatus for augmenting the yield from oil wells.

An important object of the invention is the provision of a method and apparatus which is applicable to existing wells to renew or increase this output, or which may be employed with equal facility in low yield shale and oil sands and in fields where normal procedures for development of the oil deposits are not practicable.

A further object of the invention is the development of a simple method and apparatus which shall concurrently condition the oil strata for increased oil flow and effect an increased output from the oil field.

An additional object of the invention is the provision of a novel method of heating the oil sands surrounding a well by the initiation and maintenance of a substantially constant gas flame therein whereby the oil in said sands is occluded by the resulting heat and pressure of the expanding gaseous products of combustion to adjacent wells for recovery therefrom.

A further object of the invention is the provision of simple and effective apparatus for carrying the method into effect.

A still further object of the invention is a novel method of treating an oil sand strata by forcing heated gases under pressure therethrough from within a well, thereby applying gaseous pressure to said strata for driving the oil away from the well for recovery in adjacent wells, and wherein the gas pressure is variable and with corresponding variation in the temperatures thereof whereby the oil in the sand strata may be re-formed for subsequent recovering of the products thereof from adjacent wells.

A still further object of the invention is the provision of means forming an insulated, sealed combustion chamber in the bottom portion of a well casing which extends into an oil sand strata, which casing is provided with perforations in its cylindrical wall, and continuously admitting combustible charges of gas and air into said chamber, together with means for intermittently projecting a flame into said chamber for effecting and maintaining continuous ignition and burning of the combustible charges introduced continuously within the chamber whereby the pressure developed therein by the expanding burning charges, plus the internal pressure in the well, drives the resulting heat outwardly through the perforations and into and through the surrounding oil

2

sand strata for forcing the dormant oil therein to flow toward adjacent wells for recovery therefrom.

With the above recited and other objects in view, the invention is set forth in the following specification and illustrated in the accompanying drawing, wherein—

Fig. 1 is a vertical sectional view somewhat diagrammatic in nature and illustrating the application of the invention in accordance with a preferred embodiment thereof;

Fig. 2 is a broken top plan view of the structure illustrated in Fig. 1.

Referring now in detail to the drawing, the numeral 10 designates a cylindrical casing extending down through and into an oil bearing sand strata S. The casing 10 is provided with a top closure plate 11 and is also provided near its lower end with perforations 12 in its cylindrical wall for escape of combustion gases G from within the casing to the oil sand strata S. This lower end portion of the casing 10 is partitioned from the upper portion by a packing member 16 to provide a combustion chamber C later to be described.

A plurality, preferably three, of pipes 13, 14 and 15 extend downwardly through the top closure plate 11 and into the casing 10 with their lower free ends evenly terminating within the combustion chamber and below the top of the oil sand strata S, as illustrated. These pipes 13, 14 and 15 are preferably closely disposed and extend through the suitable insulating and packing member 16 forming the top of the combustion chamber C. Thus, the interior of the casing 10, below this packing member 16, provides a combustion chamber with the free ends of the pipes 13, 14 and 15 protruding into the upper end thereof.

The pipes 13 and 14 are respectively provided with suitable regulating valves 17 and 18, and the pipe 15 is provided with a back check valve 19, the latter pipe being further provided intermediate the valve 19 and closure plate 11 with a suitable ignition means such as a spark plug 20 which may be incorporated in any suitable ignition circuit. The pipe 13 is preferably provided with a pressure gage and relief valve indicated at 21 and 21^a, and a vent pipe 22 is provided in the top closure plate 11 permitting the escape of gases that may accumulate above packing 16 to the atmosphere. Furthermore, a meter 21^b may be provided in pipe 13 beyond valve 17, as indicated.

While the pipes 13, 14 and 15 are disclosed as having closely disposed lower free ends, such

ends may communicate with a suitable unit burner.

In the operation of the structure disclosed, a suitable gas is constantly admitted through pipe 13, which is regulated in its flow by means of valve 17, and discharged into the upper end of the combustion chamber. Air or other combustion supporting medium is likewise constantly admitted through pipe 14 to the combustion chamber C, the flow of which is controlled by valve 18. A mixture of gas and air, in proper combustible proportions, is admitted through pipe 15 past the check valve 19 to the combustion chamber adjacent the discharge ends of pipes 13 and 14.

When the pipe 15 is filled with the combustible gas and air mixture to the lower end thereof or slightly thereafter, the valve 19 is closed, plug 20 is energized to ignite the mixture with the result that a flame travels down the pipe 15 and upon reaching the lower end thereof insures certain ignition of the gas and air issuing from pipes 13 and 14 which become mixed for efficient combustion. The ignition within the chamber is like any gas burner, and the hot combustion gases G will be forced through the perforations 12 into and through the oil sand strata S, as indicated by the arrows in Fig. 1.

Due to the continuous ignition of the constantly supplied combustible charges within the chamber C, the heated gases G generated therein will be driven constantly therefrom and further through the oil sand strata S with the resultant heating of all of the oil therein and driving of the same to adjacent wells for recovery therefrom. The combustible mixture traveling through pipe 15 must be rather rich to ensure the travel of a flame through the pipe if it be of any substantial length. Alternatively, other suitable ignition means may be introduced through pipe 15.

The pressure relief valve 21a may be adjusted for any desired maximum pressure within the chamber C or may be employed to vent the chamber when desired. Higher pressures with correspondingly higher temperatures within the chamber C may be obtained by admission of the gas and air through pipes 13 and 14 at higher pressures whereby the oil within the sand strata may be cracked or re-formed and the products thereof recovered from adjacent wells.

Having thus described my invention and in what manner the same may be carried into practice, what I claim is:

1. The combination of a bore extending into an oil bearing strata, a casing having a perforated section at its lower end, an insulating and packing partition in said casing above the perforated section forming a chamber freely communicating with the face of said strata, a plurality of parallel valved conduits extending into said bore and through said partition and terminating adjacent each other in said chamber, means for separately introducing the constituents of a combustible mixture through two of said conduits, means for introducing a combustible mixture through a third of said conduits, means for intermittently igniting said latter mixture above said casing for igniting and maintaining combustion of said constituents in said chamber.
2. The combination of claim 1 including means for limiting the maximum pressure in said chamber including a pressure relief valve in one of said conduits.

RALPH M. STEFFEN.
